Attorney.

UNITED STATES PATENT OFFICE.

HEINRICH ORTGIES, OF ERFURT, GERMANY.

SELF-LOADING PISTOL.

1,382,313.

Specification of Letters Patent. Patented June 21, 1921.

Application filed April 1, 1919. Serial No. 286,817.

To all whom it may concern:

Be it known that I, HEINRICH ORTGIES, citizen of the German Republic, residing at No. 30 Cyriakstrasse, in the city of Erfurt, 5 Germany, have invented certain new and useful Improvements in Self-Loading Pistols, of which the following is a specification.

The present invention relates to automatic 10 firearms, and in particular to automatic pistols having a breech slide guided in a frame, in which an automatic release is effected between the trigger and the sear when the breech slide moves backward in order to 15 prevent an unintended continuous firing. According to the present invention the interrupter effecting the said automatic release is disposed immediately in front of the sear, in which it is shiftable vertically to the longitudinal axis of the pistol. 20

In the accompanying drawing the invention is exemplified in a constructional form in an automatic pistol which is fitted with a breech slide guided on the frame. Figure 25 1 is a side elevation of the cocked pistol shown partly in section. Fig. 2 is a top view of the frame without the breech slide, but with the trigger and the sear with the interrupter. Fig. 3 shows the sear and the 30 trigger separately on an enlarged scale. Fig. 4 is a section along the line 4-4 in Fig. 3, and Fig. 5 is a top view of the sear alone.

The pistol shown in the drawings consists in known manner of the frame *a*, the barrel *b* and the breech slide *c*, said slide being guided longitudinally on the frame *a* and being so arranged that it encircles the barrel *b*. A spring acts on the slide *c* which, 40 after the shot, performs a to and fro movement on the frame *a*. In the constructional form shown in the drawings the sear is disposed on one side of the pistol. It consists of a lever provided with a pivot pin *e* which is mounted in an opening in the wall 45 of the frame. The rear end of the sear which can engage with the percussion pin *g* (Fig. 1) is permanently held up by means of a spring *f*, while its front end *h* is coupled by means of the interrupter with the 50 trigger *k*, which is pivoted on the pin *i*, and is under the action of a spring *l*. The front end *h* of the sear *d* is made in the form of

a bridge or fork in the outer branch of which is formed a guide opening wherein 55 a stud *m* constituting the interrupter is slidably mounted, said stud having an enlargement in the form of a disk *n* and being pressed outward by means of a spring *p* which bears against the other branch. The 60 outer end of the stud *m* passes through the adjacent side of the frame *a* and protrudes therefrom (Fig. 2). When the breech slide *c* is in closed position, the projecting part of the stud *m* engages in a groove in the 65 inner surface of the breech slide, and when the slide moves backward it forces the said stud inwardly. The trigger *k* has on its side a lug *q* extending upward, which bears against the disk *n* of the interrupter *m*, 70 when the latter is forced out (Figs. 2 and 5). On the trigger *k* being pressed, the sear *d* is raised, whereby the percussion pin is released, and the shot is fired. The breech slide *c*, which is then thrown back, thereby 75 forces the interrupter *m* inward, so that the lug *q* of the trigger *k* is disengaged from the disk *n* of the interrupter (Fig. 4). The sear can then again resume its normal position, and catch the percussion pin when the latter has reached the end of its rearward 80 movement. The trigger can engage with the sear *d* only after it has been released by the operator. It goes without saying that the interrupter may also be used with 85 a sear of any other type than the one shown in the drawings.

What I claim to secure by Letters Patent of the United States is:—

In a firearm, the combination with the 90 breech slide and the trigger; of a sear having a forked front end, the outer arm of which is provided with a guide opening; and a spring controlled stud slidably mounted in said opening and provided with a portion which is normally disposed in the path 95 of the trigger to operatively couple the latter to said sear, but which is automatically displaced from said path consequent upon the rearward movement of the slide to prevent operation of the sear by the trigger when the breech is open.

In testimony whereof I have affixed my signature.

HEINRICH ORTGIES.
